Application March 30, 1950, Serial No. 8,868

Term of patent 14 years

(Cl. D58—26)

To all whom it may concern:

Be it known that we, John K. Bruce, a citizen of the United States, residing at South Pasadena, and Thomas H. Davis, a citizen of the United States, residing at Alhambra, both in the county of Los Angeles and State of California, have invented a new, original, and ornamental Design for Combined Carrier Package and Cans, of which the following is a specification, reference being had to the accompanying drawing, forming part thereof.

Figure 1 is a perspective view of a combined carrier package and cans, showing our new design.

Figure 2 is a longitudinal, medial vertical sectional view of the combined carrier package and cans of Figure 1.

The back and side views not shown are the same as those shown.

We claim:

The ornamental design for a combined carrier package and cans, substantially as shown and described.

JOHN K. BRUCE.
THOMAS H. DAVIS.
